UNITED STATES PATENT OFFICE.

WILLIAM I. SILVERSTEIN, OF BROOKLYN, NEW YORK.

MACHINE FOR MAKING VENTILATORS FOR WEARING APPAREL.

Application filed November 15, 1924. Serial No. 750,187.

My invention relates to machines for forming and stitching tape in strips provided with ventilating openings to be embodied in articles of wearing apparel; and its objects are to feed the tape to the stitching mechanism while forming ventilating openings in the work, to coordinate the feeding means and stitching mechanism, to provide a new guiding mechanism for forming the ventilating strip, and generally to simplify and make more effective the operation of the several parts of the machine.

Attention is hereby directed to the accompanying drawing, in which similar numerals of designation refer to similar parts throughout the several views: Figure 1 is a side elevation of my improved machine; Fig. 2 is a horizontal section on line 2—2 of Fig. 1 looking in the direction of the arrows, 20 and Fig. 3 is a vertical section on line 3—3 of Fig. 1 looking in the direction of the arrows.

Referring to the drawing, upon the stitching machine 4 which is of the usual construction well known to the art, I mount my improved mechanism for feeding and forming the ventilating strip. For this purpose the shaft 5 is provided with a helical gear 6, which is secured thereto by means of the sleeve 7 and set screw 8, the said sleeve 7 being integral with the said gear. At one end of the shaft are the pulleys 9 and 10, which are connected with a suitable source of power.

Meshing with the helical gear 6 is the helical gear 11 mounted on the shaft 12, which is journaled in suitable bearings to the bracket 13 fastened to the main frame. Also mounted upon the shaft 12 is the small gear 14, which meshes with the gear 15 mounted upon the shaft 16, which is journaled in suitable bearings in the said bracket 13. Also mounted upon the shaft 16 is the beveled gear 17 which meshes with the beveled gear 18 mounted on one end of the shaft 19, the shaft 19 being journaled in suitable bearings in the lateral projections 20 and 21 of the bracket 13.

At the other end of the shaft 19 is mounted the beveled gear 22, which meshes with the beveled gear 23 mounted upon one end of the shaft 24, which is also journaled in bearings on the bracket 13. At the opposite end of the shaft 24 is mounted the crank 25, the free end of which is provided with the button 26, the shank of said button moving freely in the slot 27 of the finger 28. One

end of the shaft 16 is provided with a crank 29, upon the free end of which is mounted the button 30. The shank of said button 30 is shaped to engage with the slot 31 of the finger 32. The finger 32 is mounted upon the slide 33 and the finger 28 is mounted upon the slide 34. As will be seen from Fig. 1 the slide 33 is provided with a tape opening 35 and the slide 34 is provided with a tape opening 36. The loop 37 secured to the table 38 of the main frame, encloses the said slides 33 and 34 as does also the loop 39, which also is mounted upon the main frame. The loops 37 and 39 serve to keep the two slides 33 and 34 in proper alignment.

In addition to the table 38, the apparatus is provided with the well known needle 42 and advancing mechanism 49. The idler roll 48 is of special construction, the periphery thereof being provided with spikes which, co-operating with the mechanism 49, prevent the lateral displacement of the work while being sewed by the needle 42. The thread and mechanism for feeding the same to the needle is old to the art, and for the purpose of clearness is not shown in the drawing. The stitching mechanism is operated from the shaft 5 in the manner well known in the art.

The operation of my improved machine is as follows: The tapes 50, 51 and 52 are fed into the tape openings 35, 36 and 41 respectively in the front of the machine, the opening 41 being stationary, and acting as a guide for the tape 52. As the tape is being fed and is drawn in by the aid of the idler roll 48 and the advancing mechanism 49, the slides 33 and 34 slip laterally one upon the other to criss-cross the tapes 50 and 51, the tape 52 proceeding through the machine in a straight line. At the same time the needle 42 operates to sew through the central tape 52 and through the tapes 50 and 51 at said crossings while being held against lateral displacement by said roll 48 and mechanism 49. The arrangement of parts and timing of the gears is such that when the cranks 25 and 29 are in a horizontal position, the tape openings 35 and 36 are at their greatest distance from each other, and when the said cranks are in vertical position, the tape opening 35 is directly over the tape opening 36, the result of such arrangement being to form the tape into the ventilating strip 45. (See Fig. 2.) As will be observed the ventilating strip is provided with the

openings 46 and has a line of stitching 47 directly through the center thereof.

Through my construction of the strip forming mechanism hereinbefore described and my modification of the stitching mechanism thereof, I have provided an apparatus which is new to the art and for the invention of which I believe myself to be entitled to the broadest protection. While I have herein shown and described a preferred form of my improved device, I by no means desire to limit myself to the exact construction shown, since it is obvious that various changes and modifications could be made without departing from the spirit and purpose of my invention.

What I claim and desire to secure by Letters Patent is,—

1. In a machine for making ventilators for wearing apparel, overlapping laterally sliding members for overlapping and spacing a plurality of strands, feeding and stitching mechanism for stitching together said strands cooperating with said members, and means for preventing the lateral displacement of said strands while the same are being stitched.

2. In a machine for making ventilators for wearing apparel, overlapping slides for overlapping and spacing a plurality of strands, stitching mechanism for stitching together said strands cooperating with said slides, and feeding mechanism combined with an idler roll having projections thereon for preventing lateral displacement of the work while the same is being stitched.

3. In a machine for making ventilators for wearing apparel, two members sliding later-

ally one upon the other for overlapping and spacing a plurality of strands, stitching mechanism for stitching together said strands cooperating with said members, and means for preventing lateral displacement of said strands while the same are being stitched.

4. In a machine for making ventilators for wearing apparel, overlapping slides for overlapping and spacing a plurality of strands, a central shaft, gears operatively connecting said slides with said shaft combined with mechanism for feeding and stitching together said strands operated from said shaft and cooperating with said slides.

5. In a machine for stitching tape in strips provided with ventilating openings, overlapping slides provided with rectangular openings to receive strands of tape, feeding and stitching mechanism for stitching together said strands cooperating with said slides, and means for preventing lateral displacement of said strands while the same are being stitched.

6. In a machine for stitching tape in strips provided with ventilating openings, a stationary guide for feeding one of a plurality of strands of tape, overlapping guides for overlapping and spacing the remaining strands, feeding and stitching mechanism for stitching together said strands cooperating with said slides, and means for preventing lateral displacement of said strands while the same are being stitched.

In testimony whereof I have hereunto set my hand this 14th day of November 1924.

WILLIAM I. SILVERSTEIN.
